UNITED STATES PATENT OFFICE.

WILLI A. PRAHL, OF SALT LAKE CITY, UTAH.

RAIL.

1,122,154.

Specification of Letters Patent.

Patented Dec. 22, 1914.

Application filed April 24, 1914. Serial No. 834,174.

To all whom it may concern:

Be it known that I, WILLI A. PRAHL, a citizen of the United States, residing at Salt Lake City, in the county of Salt Lake and State of Utah, have invented new and useful Improvements in Rails, of which the following is a specification.

The present invention relates to improvements in rails, and especially in means for connecting the meeting ends of rails.

In carrying out my invention it is my purpose to provide a rail chair having side members to engage with the opposite faces of the meeting ends of the rails, and to provide a key between the upper edges of the said side members and the underfaces of the heads of the rails to secure the chair to the rails and to join the meeting ends of the rails.

With the above and other objects in view, the improvement resides in the construction, combination and arrangement of parts set forth in the following specification and falling within the scope of the appended claims.

In the drawings: Figure 1 is a perspective view of two rails constructed and connected in accordance with the present invention, Fig. 2 is a transverse sectional view through one of the rails and looking toward the end of the rail chair, the arms of the said chair being in their normally spread condition, preparatory to locking the same to the heads of the rails, Fig. 3 is a similar sectional view but showing the arms in engagement with the rail and locked thereto, Fig. 4 is a sectional view similar to Fig. 2, but showing one of the sides of the chair bent to permit of the insertion or removal of the rails from the chair, Fig. 5 is a sectional view illustrating the manner in which the chair is secured upon an ordinary rail, Fig. 6 is a sectional view taken in a line with one of the connecting bolts and one of the securing spikes, and Fig. 7 is a transverse sectional view illustrating the manner in which securing plates may be arranged to engage with the opposite sides of the chair and to secure the locking nuts and bolts against rotation.

In the preferred form of my device, I provide two rails, 1-1, each of the ordinary construction except that the said rails have the underfaces of their heads at the opposite sides of their webs formed with longitudinally extending channels 2-2. Pref-

erably the underfaces of the heads are enlarged, providing angular portions, indicated by the numerals 3, the dotted lines showing the ordinary formation of the underfaces of the heads, and the said enlargements 3 may be arranged only at the ends of the rails.

The numeral 4 designates a chair member which includes a base 5 upon which the base flanges of the meeting ends of the rails rest, inturned angular flanges 6 having their ends formed with vertical plates 7 which, when forced into engagement with the rails, fully fill the fishing spaces to the opposite sides of the rails, the flanges 6 conforming to the shape of the base flanges of the rails. The members 7 are centrally channeled, as at 8, and at their reduced portions are formed with openings 9 which register with similar openings in the webs of the rails, the said openings being provided for the reception of bolts 10 which are provided with the usual securing nuts 11.

By reference to Fig. 2 of the drawings, it will be noted that the rail engaging sides of the chair are at an outward angle with relation to each other, the connecting portion 12, between the flanges 6 and the base 5, being formed of some suitable spring metal, so that the side members of the chair are normally, as stated, at an angle and also whereby one or both of the said sides may be bent to permit of the insertion or removal of the said rails, as indicated in Fig. 4 of the drawings. The upper edges of the plates 7 are beveled or inclined, as at 13, to agree with the inclined surfaces 3 upon the underfaces of the rails, and the said upper edges of the members 7 are formed with longitudinally extending channels 14, which are of a width corresponding with the width of the channels 2, and which have their lower walls beveled or inclined in the same direction as the upper walls of the said channels 2. Bolts 10 pass through the registering openings 9 in the plates 7, and nuts 11 are provided for the said bolts. The nuts, when screwed upon the bolts force the rail engaging sides of the chair against the opposite sides of the rails. The numerals 15 designate key members which are adapted to be inserted within the registering channels 2 of the rails, and 14 of the chair members. These keys correspond in shape with the walls of 110

the channels, fully filling the said channels, and the keys are of a desired length to entirely pass through the channels in the side members of the chairs. The keys are forced longitudinally in the registering channels from one of the ends of the chair. The keys projecting beyond the ends of the chair may be bent against the said ends to prevent the accidental removal of the keys.

In Fig. 5 of the drawings I have illustrated my device applied to an ordinary rail, that is, a rail which does not have the underfaces of its head formed with channels, the rail being indicated by the numeral 16. The chair 4' is substantially similar to that heretofore described, having its vertical members 9' provided upon their upper inclined edges with key-ways or channels 14', and being forced into engagement with the sides of the rails through the medium of the nuts 10' and the bolts 11'. The key, which is designated by the numeral 17, has its lower face and its sides conforming to the walls of the channel 14', but the said key preferably has its upper face rounded toward its sides, as indicated by the numeral 18. The key 17 may be slightly wedge-shaped, if desired, from its opposite faces, it being of an equal width throughout and the rounded faces 18 of the said keys forcibly contacting with the angular underfaces of the head of the rail provides an effective locking means for holding the chair upon the rails and for connecting the ends of the rails.

35 I have found it desirable to provide a spike of a special construction and locking my improved chair upon the ties. The said spike, indicated by the numeral 19, has its head 20, upon what may be termed its inner 40 side, of the ordinary construction, that is, the underface of the head from its juncture with the shank is rounded, conforming to the rounded upper portion of the flanges 6 at their connections 12 with the base portion 45 of the chair. What I will term the rear face of the spike is, however, formed with an angularly disposed outwardly projecting member 21, the underface of which being horizontally straight and being either serrated 50 or plain, the sides of the member 21 projecting, at the lower portion of the said member beyond the sides of the shank. This portion 21 limits the downward movement of the spike when the tie 22 and the enlarged portion 55 21 holds the head of the spike against danger of disengagement from the chair, as well as preventing the rotary movement of the spike or danger of the same becoming loosened or accidentally removed from the 60 tie. As illustrated in the drawings, the meeting ends of the rails are cut at an angle of about forty-five degrees so that no objectionable gap will be left between the rails 65 whereby the treads of the wheels of the

rolling stock will travel directly from one of the rails onto the other rail without danger of sinking, and also wherein the shock and jar usually incident to the passage of the train over the joint will be obviated.

In Fig. 7 I have illustrated a means for securing the chair upon the ties, and for locking the nuts and bolts which contact the side members of the chair with the rails. In this figure, the chair C has its upper edges 75 engaging beneath the heads of the rails, and the side members thereof secured to the web of the rail through the medium of a bolt B passing therethrough and engaged by a nut N. Plates P each provide a base which is 80 formed by overlapping the strip from which the plate is formed and an angular extension or lip L which engages with the angular portions of the sides of the chair. The base portion is provided with an opening through 85 which pass spikes or lag screws S which enter the ties T. It will be noted that the respective lip portions of the plate underlie one the head of the bolt, the other the side of the nut, so that the nut and bolt cannot be removed from the rail and chair until each 90 one of the plates has been removed from the tie.

From the above description, taken in connection with the accompanying drawings, the simplicity of the device, as well as the advantages thereof will, it is thought, be perfectly apparent to those skilled in the art to which such invention appertains without further detailed description. 10 95

Having thus described the invention, what I claim is:

1. In combination with the meeting ends of two rails, of a chair, said chair including a base upon which the rails rest, the base being formed with side members which conform to and engage with the sides of the rails, the vertical members of said sides being provided with longitudinally extending channels and wedge keys inserted longitudinally within the channels and contacting with the underfaces of the heads of the rails.

2. In combination with the meeting ends of two rails, each having the underface of its head at the opposite sides of its web formed with longitudinally extending channels, of a rail chair including a base upon which the rail ends rest and having sides conforming to the shape of the sides of the rails and engaging therewith, the upper edges of the sides being formed with channels which register with the channels in the rails, when the sides of the chair are forced against the sides of the rails, and keys inserted longitudinally within the said registering channels. 120 125

3. In combination with the meeting ends of two rails, each having the underface of its head at the opposite sides of its web 130

formed with longitudinally extending channels, of a chair including a base upon which the rail ends rest and having sides conforming to the shape of the ends of the rails and engaging therewith, the upper edges of the sides being formed with channels which register with the channels in the rails, when the sides of the chair are forced against the sides of the rails, keys inserted longitudinally within the said registering channels, said keys having bendable ends which are adapted to be forced into contact with the ends of the side members of the chair.

4. In combination with the meeting ends of two rails, of a chair including a base upon which the rails rest, said chair having sides shaped to conform to the sides of the rails and adapted to engage with the said sides of the rails, the sides of the chair being normally at an outward angle with relation to each other, means comprising nuts and bolts for forcing the said sides toward each other and into engagement with the sides of the rails, and wedge members between the upper edges of the sides of the chair and the underfaces of the heads of the rails for

locking the said side members of the chair to the rails.

5. In a rail joint, two alining rails, said rails having the underfaces of their heads formed at their ends with longitudinally extending enlarged portions which are angular and which are provided with longitudinally extending channels, a chair including a base upon which the rails rest, said base having sides which agree with the shape of the sides of the rails and with which they are adapted to engage, the upper edges of the sides being inclined and adapted to engage with the inclined surfaces provided upon the underfaces of the rails at the ends thereof, the said upper edges of the sides of the chair being provided with longitudinally extending channels which aline with the channels in the heads of the rails, and wedge keys inserted longitudinally within the said alining channels.

In testimony whereof I affix my signature in presence of two witnesses.

WILLI A. PRAHL.
